ALLAN R. HODGES, OF MEMPHIS, TENNESSEE, ASSIGNOR OF ONE-HALF TO CYRUS A. McALLISTER, OF MEMPHIS, TENNESSEE.

BACK-TUBE-SHEET STRUCTURE.

1,292,775.

Specification of Letters Patent. Patented Jan. 28, 1919.

Application filed February 23, 1917. Serial No. 150,513.

To all whom it may concern:

Be it known that I, ALLAN R. HODGES, a citizen of the United States, residing at Memphis, in the county of Shelby and State of Tennessee, have invented new and useful Improvements in Back-Tube-Sheet Structures, of which the following is a specification.

This invention relates to an improved 10 back tube sheet structure for locomotive boilers.

The principal objects of the invention are to provide a structure whereby the back tube sheet will not be destructively or detrimentally affected by the stresses developed in consequence of the contraction and expansion of the fire-box shell, nor by the stresses developed by its own expansion and contraction in consequence of heat; to provide a structure 20 wherein the integrity of the connections between the tube ends and the back tube sheet will not be affected by the stresses developed incident to the expansion and contraction of the fire-box shell; and to provide a simple and improved structural relation 25 between the back tube sheet and the front end of the fire-box shell whereby the riveted seam by which the jointure of the back tube sheet to the shell is effected is so located that it receives efficient protection 30 against the heat to which the back tube sheet is subjected, and whereby other important advantages are secured.

A further object of the invention is to 35 provide a back tube sheet structure whereby the back tube sheet may be removed and renewed with comparative ease and without the necessity in existing boiler constructions of the type where the shells are braced by 40 stay sheets of separating the outer shell from the locomotive barrel and disconnecting the foremost stay sheet from the outer shell and fire-box shell.

With the above objects in view, the invention 45 consists in certain features of structure and structural combination involving the front end of the fire-box shell, the back tube sheet and the jointure of said sheet to said shell. More particularly, the invention consists 50 in the provision, as a functional part of the fire-box shell at the front end thereof, of a flexible channeled frame to which the back tube sheet is secured and which is specially constructed and arranged to act, with 55 reference to said tube sheet and shell, re-

spectively, in taking up and equalizing the stresses developed by the radial and longitudinal expansion and contraction of the fire-box shell and the radial expansion and contraction of the back tube sheet, to maintain the maximum rigidity of the tube sheet 60 while permitting its expansion in consequence of heat, and to prevent the transmission of destructive stresses from the fire-box shell to the tube sheet or vice versa; and in 65 the novel relation between the said channel and the tube sheet.

What is now considered as a preferred embodiment of the invention is illustrated in the accompanying drawings, wherein:— 70

Figure 1 is a cross-sectional view on the line 1—1 of Fig. 2, looking in the direction of the arrow;

Fig. 2 is a fragmentary longitudinal section of a locomotive boiler showing details 75 of the back tube sheet structure;

Fig. 3 is a face elevation and Fig. 4 is a side elevation showing a flexible joint which constitutes a structural element of a stay sheet with which the above-mentioned channel and frame may be combined; 80

Fig. 5 is a side elevation illustrating the manner of articulating the elements of the flexible joint; and

Figs. 6, 7 and 8 are, respectively, plan, side 85 and end elevations of one of the elements of the flexible joint.

Similar characters of reference designate corresponding parts throughout the several 90 views.

The improved back tube sheet structure is applicable to any type of locomotive boiler. The boiler shown is of the Jacobs-Shupert type wherein the fire-box shell 1 and outer shell 2 are made of channeled sections 3 and 4, respectively, which are braced to one another by stay sheets 5 whose marginal portions are held between the flanges of the adjoining channeled sections and secured by the rivets 6 which connect said 100 flanges. The stay sheets 5 and sling stays 5^a may be of any suitable construction, but, as shown, are of the construction which forms the subject of my co-pending application Serial No. 150,512. 105

According to the present invention, the fire-box shell has at its front end as a part thereof, and also as a part of the improved back tube sheet structure, a frame 7 whose lineal outline conforms to the outline of the 110

back tube sheet 8, as dictated by the ordinary or standard arrangement of the tubes 9, the ends of which are secured in the usual or any suitable manner in said back tube sheet.

- 5 The frame 7 constitutes, in functional effect, the extreme front section of the fire-box shell and it has a substantially U-shaped cross-section and thereby provides a channel which opens outwardly in the transverse or 10 radial plane of the boiler. The said channel has a bow or base portion 10 of regularly curved, preferably semi-circular, cross-section and rear and front side walls 11 and 12 which are continued in parallel relation in 15 planes transverse to the boiler through a suitable extent, *i. e.* an extent sufficient to provide suitably wide bearing surfaces along the seams formed by the riveting of the frame 7 to the adjacent parts.
- 20 The frame 7 is integrally combined with and projects forward from the inner throat sheet 13; said frame is, preferably, also integrally combined with the foremost stay sheet 5; and the straight or flat channel side 25 wall 11 merges with, and becomes in fact part of, said stay sheet and throat sheet. Where the frame 7 is thus formed in combination with the stay sheet and inner throat sheet, said frame is secured directly to the 30 foremost section 3 of the fire-box shell 1 as by rivets 14 which pass through the channel side wall 11 and the adjacent flange of the said section 3, the lines of riveting being continued downward at the sides of the stay 35 sheet in the portions thereof below the sides of the frame 7.

The back tube sheet 8 consists of a flat plate of boiler steel of suitable gage whose marginal portion is extended sufficiently beyond the tubes 9 to come flush with the edge of the channel side wall 12; and the said extended marginal portion of the tube sheet 8 is secured to the said wall 12, at close and regular intervals, throughout its extent, by 40 rivets 15. The tube sheet 8 is supported by the frame 7 and at its lowest point is braced to the barrel of the locomotive by a suitable belly brace 8^a which is preferably of flexible construction and includes sections connected 45 by a flexible inter-engaging hook joint of the general character to be hereafter described in connection with the statement of the details of the stay sheet.

It is to be observed that the marginal portion of the sheet 8 and the flat channel side wall 12 have a uniform and comparatively wide bearing against one another to promote the security of their steam-tight jointure. It is also to be observed that the seam or joint 50 between the frame 7 and the back tube sheet 8 and the circle of rivets 15 by which said seam or joint is completed are located outside of the fire-box, remote from the flames and direct heat, and within the steam space 55 60 65 66 of the boiler whereby the said joint and

its rivet connections will be at all times submerged in the water in said steam space and will be most efficiently protected against the direct heat of the fire-box and against the heat latent in the back tube sheet and frame 70 75 75 80 85 90 95 100 105 110 115 120 125 130

7. The side wall 12 is located in the plane of the front water leg, its lower portion being somewhat in the rear of the lower portion of the locomotive barrel; and the submerged portion of the riveted seam or joint 75 by which it is connected to the sheet 8 is located just above or within the upper portion of said water leg. The submerged seam, therefore, does not present any obstruction to the circulation of water nor to the free removal of scale and mud deposits.

The stay sheet 5 in the special construction thereof shown, consists of an arch member 17 which is secured to the fire-box shell 1, an arch member 18 which is secured to the outer shell 2, and a series of radially disposed flexible joints 19 between the said members 17 and 18, each consisting of inter-engaging hooks 20 formed at the ends of companion radial fingers 21 with which said members are provided, each hook having a terminal lug 22 for which the companion hook has an opening 23. The arch member 18 is made in sections which are individually secured to the arch member 17 after the latter has been connected to the fire-box shell, the organization of the member 7 and the sections of the member 18 involving an initial transverse movement of the hooks 20 to aline the terminal lugs 22 with the openings 100 105 110 115 120 125 130 23, as shown in Fig. 5, and a subsequent longitudinal movement of said hooks to insert the terminal lugs 22 through the openings 23. When thus organized, bracing webs or bridges 24 are secured by welding between the lugs 22 and the fingers 21 toward which said lugs point, as shown in Figs. 3 and 4.

A stay sheet of the construction disclosed, while not obligatory in connection with the back tube sheet structure which constitutes the invention, is of special advantage in that its augmented flexibility, due to the loose play provided for by the joints 19, is effective in relieving the fire-box shell, and with it the frame 7, of severe and destructive 110 115 120 125 130 135 140 145 150 their planes, *i. e.* in the transverse or radial direction of the boiler, without impairing the stability of the form of the back tube sheet or the integrity of the connections 5 between it and the tube ends. In consequence of such flexibility, the stresses incident to the radial and longitudinal expansion and contraction of the fire-box shell will, at the front of the fire-box, be substantially absorbed and equalized by the frame 7 and will not be transmitted, at least to any detrimental extent, to the back tube sheet 8; and in like manner, the stresses in connection 10 with the expansion and contraction of the back tube sheet 8, as by changes in temperature, will be relieved or taken up and equalized by the frame 7 and will not be transmitted to the fire-box shell.

An important advantage of the structure 20 disclosed is the facility with which the back tube sheet may be removed when unfit for further use and a new one substituted. In such a case, after the tube ends have been freed from the back tube sheet the securing 25 rivets 15 of the latter are cut and the sheet, by canting it obliquely, is inserted rearwardly through the frame 7 and removed from the boiler at the rear end thereof. On such removal of the back tube sheet the 30 frame 7 is left intact and a new sheet, introduced through the rear end of the boiler and inserted forwardly through said frame, is secured in the manner disclosed to the front channel wall 12, after which the ends of the 35 tubes 9 are fitted in the new sheet. These operations do not require the separation of the outer shell from the locomotive barrel and the removal of the foremost stay sheet from the shells as is necessary in existing 40 boiler constructions where stay sheets are employed to brace the two shells.

In connection with the above noted advantage it may be observed that the frame 7,

in the construction disclosed, will serve at least as long as the fire-box of which it 45 forms an element and, therefore, will outlast the back tube sheet and serve in connection with all necessary renewals of such sheets.

I claim as my invention—

In a back tube sheet structure for locomotive boilers, in combination, a back tube sheet, a throat sheet at the front end of the firebox shell and forming the rear wall of the front water leg and a frame at the front 55 end of the firebox shell and which supports said tube sheet and forms a functional element of said shell, said frame conforming in lineal outline to the tube sheet and having a U-shaped cross section to provide a 60 channel which opens outward in the radial or transverse plane of the boiler and has a semi-circular base and parallel side walls projecting from said base, the rear side wall of said channel being secured to the fire- 65 box shell and being formed integrally with said throat sheet and the front side wall of said channel being secured to the marginal portion of the tube sheet, the seam at the jointure of said front side wall and said 70 tube sheet being located in the plane of said water leg and the submerged lower portion of said seam being located just above the water leg and somewhat in the rear of the locomotive barrel, the frame 75 and tube sheet having such outline that the tube sheet, in renewal, may be inserted, in planary form, through the opening of the frame.

In testimony whereof I have hereunto set 80 my hand in presence of two subscribing witnesses.

ALLAN R. HODGES.
